HERMETICALLY SEALED COMPRESSOR
AND VACUUM SYSTEM

John J. Davis, Lacombe, La.

Application May 14, 1946, Serial No. 669,686

2 Claims. (Cl. 308—187.1)

1

The invention relates to a hermetically sealed apparatus and more especially to a hermetically sealed compressor or vacuum system.

The primary object of the invention is the provision of a system of this character, wherein one of the difficulties of the usual compressors is the gas escaping past packing glands is overcome, in that with the system hermetically seals the power unit without the system, thus making it possible for repairs to such unit with ease and dispatch and without disturbing the system or releasing gases therefrom.

Another object of the invention is the provision of a system of this character, wherein the power unit outside of the same can operate a compressor, drive a cooling fan or pump cooling fluids and at the same time the gases in the system will not effect the power unit as well as obviating loss of such fluid.

A further object of the invention is the provision of a system of this character, which is simple in construction, thoroughly reliable and efficient in operation, strong, durable, positive in the working thereof, possessed of few parts, assuring against gas losses and inexpensive to manufacture and install.

With these and other objects in view the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is an elevation of the system constructed in accordance with the invention;

Figure 2 is an end view thereof;

Figure 3 is a sectional view taken on the line 3—3 of Figure 1 looking in the direction of the arrows;

Figure 4 is a sectional view taken on the line 4—4 of Figure 3 looking in the direction of the arrows;

Figure 5 is a sectional view taken on the line 5—5 of Figure 3 looking in the direction of the arrows;

Figure 6 is a fragmentary sectional view taken approximately on the line 6—6 of Figure 3, looking in the direction of the arrows;

Figure 7 is a detail sectional view taken on the line 7—7 of Figure 6 looking in the direction of the arrows.

Similar reference characters indicate corresponding parts throughout the several views in the drawings.

Referring to the drawing in detail, the system

2

constituting the present invention, comprises in this instance a base stand 10, for support on a foundation, to which it is secured in any suitable manner, while rising vertically from this stand 10 is the intermediate section 11 of a compressor housing having the opposed horizontally arranged outer compression cylinders 12, which are provided with external inner end annular flanges 13, through which pass fasteners 14 for securing to the section 11 and in this manner the latter and the cylinders 12 are united together.

Within the cylinders 12 work pistons 15, which are connected by a coupling stem 16, one only, and having opposite threaded ends 17 tapped centrally into the said pistons 15 for the reciprocation of the latter together with alternating in and out strokes thereto.

Built into one side cheek 18 of the section 11 of the housing below the plane of the cylinders 12 which protrude laterally from opposite ends of this section 11, is a tubular gland body 19, which removed from its inner end protruding into the said housing has formed therewith an external attaching flange 20 fastened by fasteners 21 to the cheek 18. The inner and outer ends of the gland body 19 are equipped with caged ball bearings 23 and 23a respectively, for a rocking crank shaft 24, centered within said body 19, with its crank 25 confined within the section 11 next to and at one side of the stem 16 sweated within the lower end of the body 19 adjacent the bearings 23 is a closure cap 22 for the sealing of the lower end of the body 19. This crank 25 has link connection 26 to the stem 16, so that when the shaft 24 is oscillated by a power unit not shown, having connection thereto by an operation arm 27 fitted at 28 to the outer end of such shaft 24.

Within the gland body 19 and about the shaft 24 is a sleeve-like flexible oval and tapered sealing membrane 32, which comprises a plurality of slidably related oval shaped ring members 32a having offset sealing end flanges 32b and 32c respectively, see Figure 7, which prevent leakage of the gas during the rocking motion of the shaft 24. The membrane 32 has its smaller end 29 sealed to a collar 30 snugly embracing the shaft 24, while its larger end 31 is sealed against a second collar 36 snugly embracing the shaft and next to the bearings 23a and oval shaped fastening means 29a and 31a respectively seal the ends 29 and 31 of the membrane to the collars. The fastening means 29a and 31a being recessed in their respective collars and the collars having a close tolerance with the interior of the body. In this manner the gland is rendered fluid tight to

avoid gas leakage there through from the compressor housing, the cylinders 12 thereof being provided with fluid inlet and outlet parts 33 and 34, which are provided with check return valves not shown, of any suitable construction.

It would be seen that the compressor and adjuncts are sealed within a sealing system, adaptable for refrigerating plants, so that the power unit will be outside of the system, for easy access and is not subjected to gases within such system and used for refrigeration.

What is claimed is:

1. A sealing construction for use with a rocking shaft within a hollow housing comprising roller bearing units mounted in the ends of said housing and receiving the shaft, a sealing cap carried by one end of the housing outwardly of one of the bearing units at the end of the housing and receiving the shaft, collars on the shaft inwardly of the roller bearing units, oval recesses in the inner faces of the collars, oval shaped fastening means seated in the recesses and a flexible membrane composed of a plurality of oval shaped

slidable ring shaped members fixed at the opposite ends to said collars by said fastening means.

2. The invention as in claim 1 wherein the ends of said ring shaped members are provided with offset flanges for the sealing of said members.

JOHN J. DAVIS.
